UNITED STATES PATENT OFFICE

2,265,738

ELECTRICAL APPARATUS

Claude L. Matthews, St. Louis, Mo., assignor to
W. N. Matthews Corporation, St. Louis, Mo., a
corporation of Missouri

Application September 2, 1939, Serial No. 293,167

3 Claims. (Cl. 200—114)

This invention relates to electrical apparatus, and with regard to certain more specific features to electrical line protection apparatus.

Among the several objects of the invention may be noted the provision of an improvement in means for supporting the fuse holder shown in United States Patent 2,103,056 issued to Theodore Birkenmaier on December 21, 1937, wherein direct fastening to a line is eliminated while the advantages of a freely suspended fuse holder are retained and the functions thereof improved upon; and the provision of apparatus of the class described which is simple in operation and economical in cost. Other objects will be in part obvious and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawings, in which are illustrated several of various possible embodiments of the invention:

Fig. 1 is a plan view of one form of the invention;

Fig. 2 is a front elevation of Fig. 1;

Fig. 3 is a right-side elevation of Fig. 2;

Fig. 4 is a fragmentary section taken on line 4—4 of Fig. 2;

Figs. 5, 6 and 7 are related views similar to Figs. 1, 2 and 3, respectively, showing a modification;

Figs. 8 and 9 are related views similar to Figs. 1 and 2 respectively, showing a third form; and,

Fig. 10 is a detail section taken on line 10—10 of Fig. 9.

Similar reference characters indicate corresponding parts throughout the several views of the drawings.

Referring now more particularly to Fig. 1, there is shown at numeral 1 a line wire to which it is desired to electrically connect a fuse holder. This wire 1 is carried on an insulator 3 on pole 5, being held by the wires 7. A saddle 9 and a U-bolt 11 together grip the insulator 3 to support an extending cantilever arm or support 13, the outer end of which has a depending extension or carrier 15, carrying at its bottom a socket 17. From the socket extend flaring guide fingers 19.

Pivoted in a clevis 2 at the upper end of the extensions 15 is a latch 21 which is normally biased by a spring 23 (Fig. 4) to a latching position above said socket 17. The amount of bias given to the latch 21 by the spring 23 is limited

by a T-shaped extension 25 which extends through a slot 27 in the member 15. Thus the latch 21 is normally pressed to the right. When the latch 21 is in its furthermost position toward the right, it obstructs the outlet from the socket 17, but when pressed to the left (as shown in Fig. 4) against bias of spring 23, it does not obstruct the outlet.

The fuse carrier comprises an upper contact 29 having a screw cap 31 for fastening the upper end of a fuse link 33. The contact 29 has formed therewith an eye 35 with which cooperates a lug 37 of the head of a lineman's stick S. The purpose of this cooperation is to mount the fuse support on the end of the lineman's stick for application and removal to and from the holder.

From the lower end of the contact 29 extends an insulating tube 38, the latter passing through and being held to a lower contact 39. The fuse link 33 extends out from the open lower end of the tube 38 and is held by a clamp member 42, part of which consists of an arm 40 having a finger 43 over the link 33 so that pull from the link locks the clamp. At 44 is shown a flexible conductor which connects the clamp 42 with the lower contact 39. Around the conductor 44 and reacting between the clamp 42 and a lug 43 is a coil spring 41. A wire holding openable connector 45 also forms part of the lower contact 39.

Thus, between the attachment at 43 of the spring 41 and the release clamp 42 is a flexible shunt 44. This shunt protects the spring 41 from current, so that the spring 41 will not become annealed due to heating effect of current through it. In this respect, the spring 41 differs from the corresponding flat leaf-spring 21 referred to in Birkenmaier Patent 1,935,386 (Figs. 1 and 2).

An openable connector 4 also forms part of the arm 13 for a branch wire leader 6 which at a suitable point connects to wire 1. The arm 13 being of a suitable conducting copper alloy, a plain copper alloy connector is suitable for the copper leader 6 which would be used if the line wire 1 were copper. If the line wire 1 were aluminum or the like, then a similar leader 6 would be desirable to prevent galvanic corrosion at the contact between wires. In this event there would be used an openable connector at 4 having a copper alloy part for attachment to the arm 13 and an aluminum part for the corresponding aluminum lead 6, said connector parts being permanently and non-galvanically connected. Or, if line wire 1 is aluminum and leader 6 is copper, an aluminum-to-copper connector

4 can be used to join these two elements 1 and 6 together. Such connectors are known, but one point of novelty here is in the fact that by changing the support for the fuse holder from a support on the wire 1 (as in Patent 2,103,056) to a support on an insulator 3 (as herein), there is not only avoided unsteadiness and a loading of the wire, but there is also avoided the necessity for different holder supports in the different cases of different line wires (copper or aluminum). This is because with all supports 13 made of copper alloy, copper or copper-aluminum connectors may be employed for connection through a suitable copper or copper-aluminum wire 6, to the copper or aluminum wire 1, as 15 the case may be.

The purpose of a spring member such as 41 and associated parts has already been described in Birkenmaier Patent 1,935,386, dated November 14, 1933. It is to withdraw and drop the lower end of the fuse 33, after the fuse blows at its upper reduced portion 47.

At the upper end of the contact 29 is a metallic extension 49 which carries a ball 51 adapted to snugly fit into the socket 17 and having formed adjacent its end on one side a flat fin 53. This fin 53 extends around the ball and down to the upper contact 29 and carries an extending portion 55.

The operation of the device is as follows:

After having placed a fuse in the fuse holder (including attachment at 42) and thus having put the spring 41 into bowed tension (Fig. 3), a lineman fastens connector 45 to wire 46. Next he applies the lug 37 of the stick S to the eye 35, as shown in Fig. 4. By this means he can lift the fuse support upward so as to move the ball 51 into the position shown in Fig. 3. The extension 49 under these conditions moves in between the guiding fingers 19, the portion 55 functioning as a rudder to keep the ball 51 directed forwardly.

As the ball 51 gravitates toward the socket 17, it engages the lug 57 on the lower end of the latch 21 and forces the latch aside against the bias of the spring 23. The parts then assume the position wherein the ball 51 is seated in the socket 17 and the latch 21 has sprung back under bias of the spring 23 to trap the ball in its socket. The lineman's stick S may be pulled down to firmly seat the ball 51 and may then be removed from the eye 35. The fuse 33 is then in circuit. It hangs steadily but swingingly from the fixed arm 13, the wire 46 being connected as required.

If the fuse blows, as under heavy overload, the engendered gases are projected expulsively from the lower end of the tube 38, thus causing a reaction along the center line of the fuse tube. Hence the fuse holder F as a whole tends to move upward. The tendency of ball 51 to move out from the seat 17 is resisted by the then shut latch 21.

In order to remove the fuse holder, the lineman's stick S is reapplied and the fuse holder pushed upward as indicated in Fig. 4. Inasmuch as the upward motion of the ball 51 is resisted by the latch 21, there is a tendency to rotate the fuse holder. The length of the wire 46 is such as to permit this rotation, or it may be removed.

The rotation causes the fin 53 to come into contact with the lower lug 57 of the latch 21 to push it aside. This contact also causes a fulcruming of the fuse holder to occur at the lug 57, whereupon the ball is automatically pushed

out by the return biasing action of the latch. After complete removal of the fuse holder, the latch 21 is back in position, ready for the application of another or the same re-fused holder.

5 It will be clear that the reaction of the fuse blowing is not delivered to the wire 1, as is the case in Patent 2,103,056, nor is this wire 1 in any other way interfered with by loading it.

It will be quite clear that the detached lower portion of the fuse 33 after being withdrawn from the tube 38 will cease to tension the arm 101. Thus, the clamp 42 will automatically open and drop the lower portion of the link 33. At the same time the spring 41 straightens out. In this respect the action is similar to that described in connection with Figs. 1 and 2 of said Birkenmaier Patent 1,935,386. It is to be understood, however, that the use of the coil spring 41, together with the shunt 44, has the advantage above stated, namely, that current needs not to pass through the spring.

It should here be noted that the tube 38, or at least its interior, is formed of horn fibre which has a de-ionizing effect on an electric arc which tends to extinguish it. Thus, any arc due to melting of the fusible section 41 tends to be extinguished by the de-ionizing effect of the horn fibre tube 38. This tends to reduce the reaction on arm 13 because the expulsive action from the lower end of the tube 38 is less.

Figs. 5-7 show an alternative form of the invention in which like numerals designate like parts. Differences are as follows:

The arm 13 carries a non-removable connector 8 for wire 6 and the insulator 12 does not carry line wire 1 which is not shown in Figs. 5-7. The clamp 9, 11 of Figs. 1-4 has substituted therefor the one-piece spring clamp 10. The insulator 12 supports parts forming a lightning arrester to a ground wire 14.

At numeral 61 is a supporting bracket for the vertically arranged insulator 12. As indicated, the bracket 61 is formed as a split clamp 63 held to the lower end of the insulator 3 by means of a bolt 65. At 67 is a holder which affords a support for the ground wire connector 14. Extending from the clamp 63 is a threaded socket 69 for receiving the threaded end of a lower conducting gap arm 71. A lock nut 72 holds the gap arm in predetermined adjustment, after adjustment, both longitudinally and angularly. The arm 71 is bent to one side of its normal plane as shown in Fig. 6.

The upper clamp 10 supports in a similar way an arm 71 offset an equal amount oppositely (see Fig. 5).

Each conducting gap arm 71 has an outwardly extending straight portion. Beyond the straight portions each arm is turned at a right angle as indicated at 73. The angled portions are directed toward one another. Then there are formed loop or turn portions 75 with outwardly extending horn portions 77. The portions 77 relatively flare out toward the left.

At a mid-point on the insulator 12 is provided a third clamp 79 having a clamp bolt 81. Clamps of this type are made very malleable so that they may be opened and reclosed around the waist which they encircle. Two-piece clamps may also be used. In this case the threaded socket 80 carries a threaded stem 83 locked by means of another lock nut 84. The stem 83 carries at its outer end a loop or ring-like member 85, which is shown circular. The plane of the circle is midway between those of the gap arms 71.

The operation of the lightning arrester is like that specified in said application, except that therein the offset between arms 71 and 83 prevents short-circuits due to dripping rain or pendent icicles.

It will be noted that the offset or stagger of the conducting portions 75 are opposite with respect to the intermediate conductor member 85. This permits of obtaining the same gap above and below the member 85 without introducing short-circuiting due to pendent icicles. For instance, if the upper member 75 were adjacent to the left in Fig. 6, instead of to the right, then for equal gaps the upper member 75 would be directly over the lower member 75, thus reintroducing the difficulty due to short-circuiting from icicles and the like. Under such conditions the only way to avoid a coplanar relationship between the members 75 would be to make the gaps unequal, which is not desired. Thus it will be seen that by having the respective members 75 staggered oppositely with respect to the intermediate member 85, none of the three electrodes in the surge arrester is in the plane of the other, and equal gaps may be maintained respectively between the upper and lower conductors and the intermediate conductor.

It will be understood in connection with Figs. 5-7 that any overload or short-circuit on the line (with which wire 6 is connected) will melt the fuse in the fuse holder 38, and that any, or at least most, transient voltage surges such as lightning will be by-passed to ground over the gaps between parts 71 and 83 and ground wire 14.

In Figs. 8-10 a construction without a lightning arrester is shown, wherein a flexible supporting cantilever arm is used. In this case an inner arm portion 91 is attached or anchored to the top of an insulator 93. An outer arm portion 95 supports the fuse holder parts, as shown at set screws 20, like numerals designating like parts in respect to the fuse holder parts. This outer portion 95 also carries a lug 97 for a wire connector 98.

To resiliently connect parts 91 and 95 they are tightly threaded into a relatively stiff (but yieldable) spring 201 which, with parts 91 and 95 makes an arm stiff enough to support the fuse holder parts against the action of gravity. However, any heavy reaction forces due to blowing of the fuse in holder 38 are relieved by flexing of the spring 201 with a subsequent return to the normal position shown. Wires 46 and 6 are connected with enough leeway to allow for this action.

The arms 91 and 95 and associated elements of this embodiment can likewise with success be used in the embodiment of Figures 1, 2 and 3, in order to make the latter embodiment capable of interrupting heavier short-circuit currents.

It will be seen that the construction of Figs. 8-10, like that of the other figures, provides an upper single laterally extended support which is

relatively stiff against gravity action, which support, by means of the carrier at its end, supports the depending rigid expulsive fuse holder F. As before, the fuse holder has a quick detachable connection with the carrier, and the support is resilient enough to permit movement of the fuse holder and the carrier in responsive to expulsive reactions from the fuse holder.

Advantages of the invention are:

- (1) Avoidance of objections which are often made (validly or invalidly) to hanging items on line wires;
- (2) Elimination of time and trouble required to manipulate line wire supporting clamps, and providing for a quick-detachable connection between the fuse holder and its supporting carrier;
- (3) Elimination of the necessity for special aluminum fuse holder parts where aluminum line wires are encountered; and
- (4) Low cost and simplicity.

Further references and claims directed to cantilever spring fuse parts may be found in the United States patent application of Claude L. Matthews et al., Serial No. 298,448, filed October 7, 1939, for Electrical apparatus.

In view of the above, it will be seen that the several objects of the invention are achieved and other advantageous results attained.

As many changes could be made in the above constructions without departing from the scope of the invention, it is intended that all matter contained in the above description or shown in the accompanying drawings shall be interpreted as illustrative and not in a limiting sense.

I claim:

1. Line protection apparatus comprising a single laterally extending support which is relatively stiff against gravity action, a carrier thereon, an open expulsive fuse holder which is rigid per se and which is dependently supported against gravity exclusively by said single support, the opening of the fuse holder being directed down so that expulsive reactions are against gravity and applied to the support, quick-detachable means between the carrier and fuse holder, and a substantially resilient section in said support permitting substantial resilient movement of the carrier under operative expulsive reactions from the fuse holder.

2. Line protection apparatus comprising a cantilever member, a fuse holder supported thereby, said member having a spring section therein.

3. A support for a fuse holder comprising a round anchored member threaded at one end, a second round member also threaded at one end, said threaded ends being threaded into a common coil spring which forms a connection therebetween and means on the second member for swingably hanging a fuse holder therefrom.

CLAUDE L. MATTHEWS.
